INDUSTRIAL AMBULANCE

George Fordham, Powellton, W. Va.

Application May 2, 1936, Serial No. 77,561

5 Claims. (Cl. 105—212)

This invention relates to ambulances and more specifically to self-propelled industrial ambulances particularly adapted to use in mines.

Among the objects of the invention is the provision of an ambulance car designed to permit transportation of patients comfortably from a scene of accident or treatment within the mine, to the exterior thereof.

The invention also considers a maximum ease of riding from points within the mine to a hospital ambulance outside, and to this end means are provided whereby the patient on a stretcher, does not have to be transferred from the stretcher from the time he leaves the scene until he arrives at the hospital.

Another object contemplates a design of ambulance car in which the means of transportation is a self-contained unit, both from transportation, and patient treatment standpoints. The car is provided with its own driving motor whereby any point in the mine can be reached very readily; it is also provided with means for heating the car beneath and adjacent the stretcher, to assist in treating shock and so that the patient will not suffer from cold; and it is arranged to carry in convenient and accessible locations, all necessary first aid material and supplies, e. g., back splints are carried so that the patient can be properly splinted and possible injury to the spinal cord reduced.

The invention further contemplates use of a small ambulance car which may be coupled to a conventional motor car as normally used in a mine, and taken to any desired point, an extra box for first aid material being located on the ambulance in the space normally occupied by a motor.

In all forms of the invention, fastenings are provided for the stretcher handles to prevent shifting or displacement of the stretcher in case of derailment, and coil springs are used to absorb shock and increase the comfort of riding. Means are also provided to secure the car to the track and prevent movement while loading or unloading the patient.

To the attainment of the foregoing and other objects, which will appear as the description proceeds, reference may be made to the accompanying drawings, in which:—

50 Fig. 1 is an elevation in perspective of the am-

bulance car complete, except for the stretcher;

Fig. 2 is a fragmentary elevation of the upper or stretcher frame of the car with a stretcher in position thereon;

Fig. 3 is a fragmentary elevation showing a built-in motor drive on a self-propelled car;

Fig. 4 is an elevation of a rail grab used for clamping the car to the track, the grab being shown open; and

Fig. 5 is a similar view showing the grab closed about a rail of the track.

Referring now particularly to the drawings in which like reference numerals designate like parts, there is illustrated an ambulance car having a main frame or chassis 10 upon which is mounted an auxiliary skeleton body or stretcher frame 11 which is yieldingly separated from the chassis by suitable resilient means, illustrated herein as coil springs 12. Guide blocks 13 are secured to the chassis 10, these blocks being slotted, as indicated at 14, to receive pins 15 extending from the superstructure or upper framework 11, and serve to prevent side-sway and maintain the normal relationship between the chassis and superstructure.

25 A trolley pole 16 serves to conduct current from a conventional available source, as the trolley 17, to an electric motor 18, preferably enclosed in a metal grill or housing 19 at one end of the car. The motor 18 is suitably connected, as by a chain drive 20, to the wheels 21, illustrated in the present embodiment as of the flanged type, for use on trackage or rails 22. If desired, a sheet iron chain guard 23a may be provided.

35 A rail grab or wheel scotch 23 may be utilized to secure the car against movement during loading or unloading thereof, and as illustrated in Figs. 4 and 5, this grab comprises a chain 24 secured to the chassis of the car, and a pair of tongs 25 arranged to grab the upper flange of the 40 track rail 22. A collar 26, encircling the chain 24 may be slipped down and over the pivoted ends of the tongs 25 to secure same together.

45 Where the mine trackage is sufficient and a self-propelled car can be used, a small headlight 27 may be provided at either or both ends of the car. For mines that do not have a great amount of trackage, the car may be used without its own motor, and can be coupled to any gathering motor vehicle in the mine, to be taken to a scene of 50

accident. For this purpose a coupling 28 may be provided at each end of the car. In fact, under these conditions, a smaller, lighter car may be used.

5 The superstructure or stretcher frame 11 of the car is particularly designed to receive and adjustably accommodate a stretcher, and to this end is constructed with a built-in cross bar 29, which is notched as at 30 to receive the ends of 10 the stretcher handles, chains 31 being provided to secure the handles in place. A second cross bar 32 is built in adjacent the bar 29, in such a position that the ends of the stretcher handles, when positioned in the notches 30, may abut thereagainst, and the stretcher thus prevented from 15 sliding lengthwise of the car.

At the opposite end of the car the superstructure frame terminates in an adjustable support 33, formed by extensions of the superstructure, 20 pivoted at points 34, and connected by a notched cross bar 35 which serves to brace the extension members. The notches 30a of the bar 35, and 25 chains 31a cooperative therewith, are in all respects similar to the notches 30 and chains 31, on the bar 29, as previously described.

Braces 36 extending from the end of the adjustable support to notched portions 37 of the chassis serve to adjust the support portion 33 to 30 a plurality of different heights.

30 The space beneath the head support 33 may well be utilized for the storage of supplies, and hence a compartment 38 is provided, which may contain in addition to the usual first aid equipment, back splints for use on the patient to prevent 35 injuries to the spinal column.

In order to treat shock and also prevent the patient from suffering with cold, suitable heating means, illustrated herein as resistance heaters 39, may be located at suitable points where they will 40 do the most good. Preferably, they are located beneath and adjacent the stretcher.

From the foregoing description, the operation and advantages of the invention will be readily apparent. As shown in Fig. 2, the stretcher 40 45 will be placed with its handles 41 and 42 in the notches 30 and 30a, respectively, and the adjustable support 33 positioned at proper elevation. As the support 33 is adjusted, the stretcher 40 partakes of a gradual inclination. Now with the 50 motor attached, any point in the mine can be reached very readily and a patient placed on the stretcher, from which he does not have to be transferred, until arrival at the hospital, as the stretcher can be removed from the mine car and placed in any stretcher conveyance or hospital ambulance outside of the mine. Because of the 55 resilient mounting of the superstructure, the patient is spared shock and jars incident to movement of the mine car over the rails.

60 Inasmuch as all necessary first aid material

and means of transportation is carried on the car, same will function as an ambulance, independently of any other transportation, although as stated, in small mines the car can be coupled to any suitable motor driven vehicle, or driving medium. The cross rails 29 and 35, together with 5 their notches will, of course, be so proportioned and located relative to each other as to accommodate any standard stretcher equipment.

Having thus described my invention, what I 10 claim as new and desire to secure by Letters Patent of the United States, is:—

1. An ambulance car comprising a wheeled chassis, a stretcher frame supported in spaced relation thereto, means on said stretcher frame to support and secure a stretcher in predetermined location on said frame, and means at one end of the chassis to adjust the height of that end of the stretcher with respect to the chassis, said chassis being constructed with a built-in compartment beneath and adjacent said adjusting means.

2. An industrial mine car comprising a wheeled chassis, a stretcher frame resiliently supported in spaced relation thereto, means to prevent relative side sway between said frame and chassis, 25 means on said stretcher frame to support and secure a stretcher in predetermined location with respect to the stretcher frame, and means to adjust and fix the position of the stretcher on the 30 car.

3. An industrial mine car comprising a wheeled chassis, a stretcher frame resiliently supported in spaced relation thereto, means to prevent relative side sway between said frame and chassis, 35 means on said stretcher frame to support and secure a stretcher in predetermined location with respect to the stretcher frame, and means on said frame to vary the height and slope of the stretcher in the car.

4. An industrial mine car comprising a wheeled 40 chassis, a stretcher frame resiliently supported in spaced relation thereto, said stretcher frame having a pivoted extension at one end, means to adjust the position of said extension to different elevations, and means on said frame and said adjustable extension to secure a stretcher in predetermined position on the car.

5. An ambulance car comprising a wheeled chassis, a stretcher frame resiliently supported in spaced relation thereto, said stretcher frame 50 having a pivoted extension at one end, means to adjust the position of said extension to different elevations, means on said frame and said adjustable extension to secure a stretcher in predetermined position on the car, said chassis being 55 provided with a heating means, a built-in compartment and a driving means beneath the stretcher and within the area encompassed by the stretcher frame.

GEORGE FORDHAM. 60
